UNITED STATES PATENT OFFICE.

AUGUST LEOPOLD LASKA, OF OFFENBACH-ON-THE-MAIN, GERMANY,
ASSIGNOR TO THE FIRM OF K. OEHLER, ANILIN- & ANILINFARBEN
FABRIK, OF OFFENBACH-ON-THE-MAIN, GERMANY.

BROWN MORDANT DYE.

SPECIFICATION forming part of Letters Patent No. 767,070, dated August 9, 1904.

Application filed June 16, 1904. Serial No. 212,795. (No specimens.)

To all whom it may concern:

Be it known that I, AUGUST LEOPOLD LASKA, doctor of philosophy, chemist, a resident of 5 Gerberstrasse, Offenbach-on-the-Main, Grand 5 Duchy of Hesse, German Empire, have invented new and useful Improvements in Brown Mordant Dyes, of which the following is a specification.

In the application for Letters Patent filed 10 on my behalf on the 13th day of April, 1904, Serial No. 202,909, there are described mordant dyes which result from coupling sulfo-conjugated diazonaphthalenes with m-oxydiphenylamin. My further investigations have 15 led to the discovery that still more valuable dyestuffs are obtained by combining the sulfonic acids of heteronuclear diazonaphtholes with m-oxydiphenylamin. These dyestuffs yield on wool when dyed in an acid-bath 20 orange to violet shades, which turn into reddish brown to brownish violet on a subsequent treatment with chromium compounds acting as oxidizing agents and which are distinguished by a prominent fastness to light, 25 milling, and potting. In order to enable a most easy course of the formation of the dyestuff, it is advisable to carry out the combination of the diazo-naphthol-sulfonic acid with the m-oxydiphenylamin in a weakly-acid solution.

The following examples may illustrate the manner in which my invention is best carried out: Diazotize 59.65 parts of 2.5-amido-naphthol-7-sulfonic acid by means of one hundred and twenty-five parts of hydrochloric acid of 20° Baumé and nineteen parts of sodium nitrite. At 15° centigrade run into the suspension of the diazo compound a solution of forty-nine parts of m-oxydiphenyl-35 amin in 69.5 parts of sodium lye of 36° Baumé and three hundred parts of water, then add one hundred and thirty-six parts of sodium acetate. As soon as no more diazo compound is indicated by a test portion neutralize with soda, heat the whole on to about 40 70° centigrade, salt out, and dry. The dyestuff thus obtained forms a brownish-black powder, dissolving in water a yellowish brown

and in concentrated sulfuric acid with a violet color. The aqueous solution is rendered 50 somewhat darker on adding sodium lye. On adding hydrochloric acid the dyestuff separates as a reddish-brown precipitate.

In the following table I shall describe the tinctorial properties of some coloring-matters 55 obtainable by the above process, viz:

Dyestuff from m-oxydiphenylamin combined in an acid solution with the diazo compound from—	Dyes wool—	
	From an acid-bath.	On subsequently treating with a chromium agent.
2.5-amidonaphthol-7-sulfonic acid.	Reddish brown...	Dark brown.
2.8-amidonaphthol-6-sulfonic acid.	Orange.....	Dark reddish brown.
1.5-amidonaphthol-6-sulfonic acid.	Yellowish brown.	Yellowish dark brown.
2.8-amidonaphthol-3-6-disulfonic acid.	Reddish brown...	Dark reddish brown.
1.8-amidonaphthol-3-6-disulfonic acid.	Reddish violet...	Brownish violet.

Now, what I claim, and desire to secure by Letters Patent, is the following:

1. The process of making mordant-dyeing monoazo dyes consisting in combining in an acid solution m-oxydiphenylamin with the 75 sulfonic acids of heteronuclear diazonaphthols, substantially as described.

2. As new articles the coloring-matters which result from combining the sulfonic acids of heteronuclear diazonaphthols in an 80 acid solution with m-oxydiphenylamin which form blackish-brown powders, dissolve in sulfuric acid to a violet in water to a yellowish-brown to brownish-violet solution, from which hydrochloric acid precipitates the dyestuff 85 and which yield on wool on dyeing from an acid-bath orange to violet shades, being converted into reddish brown to brownish violet on subsequently treating with chromium compounds acting as oxidizing agents, substantially as described.

3. As new articles the coloring-matters, which result from combining the sulfonic acids of heteronuclear beta-diazo-alphanaphthol, which form blackish-brown powders, 95 dissolve in concentrated sulfuric acid to a

violet, in water to a brownish solution, from which hydrochloric acid precipitates the dye-stuff which dye on wool from an acid-bath orange to reddish-brown shades being converted into a dark brown on subsequently treating with chromium compounds acting as oxidizing agents, substantially as described.

In testimony that I claim the foregoing as

my invention I have signed my name, in presence of two witnesses, this 4th day of June, 1904.

AUGUST LEOPOLD LASKA
